HYDROCARBON SWEETENING

Elmer H. Bender, Phillips, Tex., assignor to
 Phillips Petroleum Company, a corporation of
 Delaware

Application October 28, 1941, Serial No. 416,876

2 Claims. (Cl. 196—30)

This invention relates to the sweetening of gasoline and other petroleum hydrocarbon oils and comprises an improved process of carrying out the sweetening operation and apparatus for carrying out this process. More particularly the invention relates to improvements in the sweetening of gasoline by the cupric chloride solution method shown in Schulze et al., U. S. 1,964,219, and in Henry et al., U. S. 2,089,373.

In the sweetening of gasoline or the like by the so-called liquid copper sweetening process, the sour gasoline is intimately and vigorously contacted with an aqueous solution of a cupric salt, usually copper sulfate, and a soluble chloride, such as sodium chloride, to convert the mercaptan content of the gasoline to the less objectionable, substantially odorless disulfides. The mixture is then allowed to settle and separate, whereupon the bottom layer of aqueous salts is removed from the upper gasoline layer. Usually the sweetened gasoline layer is next contacted with a stabilizing agent such as an alkaline sodium sulfide solution which serves to remove any traces of copper compounds and prevents any color instability or other deterioration of the product. The copper sweetening agent is regenerated by blowing with a free oxygen-containing gas such as air; and recirculated for further use.

Certain gasolines or hydrocarbon oils are difficult to sweeten by the conventional copper sweetening method described above. This is believed to be due largely to the concentration and type of mercaptan sulfur contained in these oils which prevents conversion thereof in the ordinary commercial installation of the copper sweetening process.

Since the sour oils and the aqueous copper treating solution are immiscible, it is necessary to obtain intimate contact therebetween while at the same time preventing too fine a subdivision of the oil and the sweetening solution. A centrifugal mixing pump is generally employed to effect the contact in the normal installation. Obviously the time of contact in such a pump is necessarily of limited duration.

In the treatment of oils which are difficult to sweeten, I have found it to be impossible to effect the desired degree of contact for a sufficient period of time to render these oils sweet to the standard doctor test, using the conventional copper sweetening process and apparatus. In addition, in the treatment of ordinary oils, very frequently it is difficult to attain the desired sweetening effect in the period of contact time attainable in the ordinary installation using a

conventional centrifugal mixing pump, or equivalent contactor, installed in the conventional manner, to effect the contact between the sour oil and the copper sweetening solution.

An object of the present invention is to improve the effectiveness of known liquid copper sweetening processes.

Another object is to increase variety of types of sour hydrocarbon oils susceptible to sweetening by liquid copper sweetening processes.

Still another object is to increase the time of contact between the sour oil and the copper sweetening solution.

Another object is to provide an improved liquid copper sweetening process.

Another object is to provide improved apparatus for carrying out this improved liquid copper sweetening process.

Numerous other objects will be apparent from a consideration of the following detailed description of a preferred embodiment of the present invention, taken in connection with the accompanying drawing, in which the figure illustrates diagrammatically one form of apparatus of the present invention by which my improved process may be carried out.

In one aspect the invention involves establishing an endless circuit of the mixture of gasoline and copper solution, which circuit includes a contactor and is largely formed by conduits exterior of, but in series with the contactor, introducing sour gasoline into the circuit by one line, introducing copper solution into the circuit by a separate line, and withdrawing a predetermined portion of the mixture preferably at a point in the circuit just before the point where the fresh sour gasoline is introduced, the whole process being conducted continuously. In the endless circuit referred to, a portion of the mixture is re-circulated again and again, depending upon the amount of by-passing employed. Preferably, also, the point of withdrawal of the mixture to the separating tank from the endless circuit is located at a point well removed from the point of introduction of the copper solution, the latter point being well removed from the point of introduction of the gasoline.

In a somewhat more specific aspect, the invention involves the considerations set forth in the preceding paragraph and, in addition, the interposition of a relatively long, relatively large, low velocity mixing zone between the point where the by-passed mixture joins the incoming sour gasoline and the point where the copper solution enters the circuit.

Referring particularly to the accompanying drawing, a motor driven centrifugal mixing pump is indicated at 1 and a separating tank at 2, in which gravity separation of the treated oil and the copper solution takes place. Sour oil to be sweetened enters the system through line 3, controlled by valve 4, at a point on a level with or higher than tank 2, and flows downwardly through an expanding connector 5 into a line 6 of considerably larger internal diameter than line 3, line 6 preferably having a diameter at least twice that of line 3 in order that the velocity in line 6 may be relatively low.

The copper treating solution is fed into line 6 via line 7 controlled by valve 8. Line 7 enters line 6 at a point 9 closely adjacent the bottom of the relatively large line 6 near the inlet of pump 1.

The outlet side 11 of pump 1, which is relatively large, discharges into relatively small vertical line 10, connected to the outlet of pump 1 by means of reducer 12. Line 10 discharges into the separating tank 2. Line 10 is provided adjacent its lower end with valve 18 which with valves 4, 8 and 14 is employed to proportion the relative amounts of gasoline entering via 3 and of copper treating solution entering via 7.

A by-pass line 13 connected to line 10 at point 16 and controlled by valve 14 places line 10 in communication with line 3 at a point 15 above the reducer 5.

In operation, sour gasoline is charged to the system through line 3 and passes downwardly through reducer 5 into the top of line 6, where its velocity is considerably reduced. At it passes by the point 15, it is mingled with by-passed mixture entering through line 13. The mixture entering line 6 has its velocity materially reduced as it enters, and passes relatively slowly downwardly under the combined influence of gravity, the suction of pump 1, the pressure on the material in line 13, and the pressure on the entering sour gasoline. As it thus passes downwardly in line 6, the entering sour gasoline is intimately agitated and commingled with the by-passed material and especially with the unspent cupric compounds in the aqueous phase thereof, causing an initial reduction of mercaptan content to disulfides.

As the mixture travelling down in line 6 passes point 9, fresh copper treating solution is added thereto by way of line 7. The mixture thus formed continues on to the pump 1, the while being further agitated and commingled, so that the fresh treating solution is intimately contacted with the recycled and new gasoline. In the pump this action is still further brought about. Due to the size of line 6 and of the inlet and outlet of pump 1, the material flows relatively slowly through line 6 and through the pump 1, which insures a long and intimate contact of the aqueous and oil phases with one another. Due to the large inlet and outlet of pump 1 and to the construction and action of this pump, the material is very thoroughly and repeatedly mixed therein.

As the material leaves pump 1 and enters line 10, its pressure and velocity are greatly increased, and it passes upwardly past point 16, where it divides, a portion passing on into separating tank 2 wherein the treated oil separates by gravity from the spent treating solution. The proportion so entering tank 2 will depend on the setting of adjustable valve 14 in line 13.

A controlled and substantial portion of the mixture in line 10 is by-passed through line 13 con-

trolled by valve 14 to be mixed with the sour gasoline entering through line 3.

Since line 10 is at a higher pressure than line 3, the by-passing referred to is readily accomplished. As will be obvious, the amounts of entering sour gasoline, of fresh copper solution, and of mixture by-passed may be conveniently adjusted relatively to one another by means of adjustable valves 14 and 18, so as to give the desired operation.

Preferably the vertical portion of line 6 is filled with suitable packing material 19 so as to increase the intimacy of contact between by-passed mixture and fresh gasoline, and, at its extreme lower portion, the intimacy of initial contact between the thus formed mixture and the fresh copper solution. For this purpose Raschig rings or Berl saddles or any other type of packing material are suitable. The packing material may conveniently be held in place by a foraminous member (not shown) placed at point 17 in line 6. Such packing material also helps to prevent layer separation in line 6.

The amount of material by-passed through line 13 may vary within very wide limits, say from about 10% to about 90% by volume of the material in line 10. Likewise the amounts of fresh sour gasoline introduced through line 3 and of fresh copper solution introduced through line 7 may vary widely relatively to one another, say from 10% of fresh gasoline and 90% of fresh copper solution up to 90% of fresh gasoline and 10% of fresh copper solution, these percentages being by volume.

By means of the present invention oils which are very difficultly sweetened by the conventional method may be sweetened in a satisfactory and economical manner without employing expensive measures such as a number of mixing pumps in series or in parallel. By by-passing a portion of the stream of partially sweetened hydrocarbon oil admixed with the copper treating solution to the sour oil charged to the system at a substantial distance above the intake of the pump and preferably maintained a relatively long, slow moving body of material before entry into the pump, a longer contact time between the sour oil and the treating solution is obtained and a much greater reduction in the mercaptan concentration of the treated oil is effected than in the conventional process.

The present invention brings about a number of important results which aid the sweetening operation, among which are the following. The dilution of the mercaptan content of the sour oil by admixture with a portion of the partially sweetened oil brings about a marked preliminary reduction in mercaptan content of the fresh sour oil and provides less work for the fresh treating solution. The much greater contact time provided by the time of travel through the line 6 and by the time of travel through the endless circuit defined by pump 1, line 10, line 13, and line 6 insures a much greater effectiveness in reduction of mercaptans to disulfides thereby enabling copper sweetening to be performed upon types of oils hitherto not feasible for copper sweetening and to be performed more effectively upon oils of the type heretofore sweetened by the liquid copper method. By the practice of my invention a sour oil of relatively high mercaptan content or containing mercaptans difficult to convert to disulfides, or both, may be satisfactorily sweetened.

The other conventional steps in the process, such as aeration of the treating solution, treat-

ment of the sweetened gasoline with a stabilizing reagent, etc., have not been described or shown since they form no part of my invention.

It will of course be understood that suitable corrosion-resistant materials of construction are used, wherever necessary, in constructing the apparatus shown in the drawing. It is also to be understood that instead of the centrifugal mixing pump 1, equivalent contactors known to the art may be used, such as an injector, a submerged orifice, a mixing T, a mixing tank with agitators therein, a conventional chemical contactor comprising a rotating shaft with blades and fixed baffles, if the contactor will of itself produce greater pressure at T 16 than exists at T 15, so that flow is maintained from T 16 to T 15. Otherwise, a pump is necessary to cause this flow from T 16 to T 15.

As will be obvious from the foregoing, the mixture which is by-passed through line 13 represents the unseparated material before opportunity for separation into aqueous and oil phases has occurred. Thus the recycled material is representative, in composition, of the material passing upwardly in line 10 and of the material passing into tank 2 for separation.

In some cases, especially where dealing with difficultly sweetenable oil, at the start of the operation before equilibrium has been established, the material passing out into tank 2 may not pass the doctor test, but will be sour. However as soon as equilibrium has been established with the by-pass line 13 properly operating, the outflow into tank 2 will be sweet to the doctor test. If after the attainment of such satisfactory operating conditions for the particular oil being sweetened, valve 14 be closed so as to shut off by-pass line 13, the equilibrium of the system will within a short time be upset or disturbed and the outflowing gasoline will register sour to the doctor test. Actual operations have thus repeatedly and continuously demonstrated the value of the invention in enabling sweetening of certain oils which would be impossible to sweeten under identical conditions except with the by-pass discontinued.

Example

Using the apparatus shown in the drawing, 120 barrels an hour of sour cracked gasoline are introduced into the system via line 3 and 80 barrels an hour of copper sulfate-sodium chloride treating solution are simultaneously introduced via line 7, these proportions being predetermined by the adjustment of valve 17 and the pressures upon each of the gasoline and the treating solution. Valve 14 is adjusted so as to allow by-passing through line 13 of approximately 100 barrels an hour of the mixture flowing up through line 10.

The gasoline separating in tank 2 is very satisfactorily sweetened, although using the particular fresh sour gasoline, it would be impossible to effect sweetening with operating conditions the same except with valve 14 closed entirely.

From the foregoing it will be seen that the present invention makes possible much wider application of the liquid copper sweetening method and presents a number of advantages over previously employed copper sweetening procedures.

It is to be understood that numerous changes and modifications may be made by those skilled in the art without departing from the spirit of my invention, which is to be taken as limited only by the terms of the appended claims.

I claim:

1. The process of sweetening a sour hydrocarbon oil which comprises introducing fresh oil to the top of a vertical elongated treating zone of relatively large cross-section, allowing the material to pass relatively slowly downwardly through said zone, introducing fresh aqueous copper treating solution adjacent the bottom of said zone into admixture with the material in said zone, rapidly and vigorously agitating the resulting mixture to obtain thorough and intimate contact of the components thereof, discharging the mixture towards a separating zone, withdrawing a portion of the discharged mixture, and introducing said withdrawn portion into admixture with the incoming fresh oil adjacent the top of said treating zone, whereby said withdrawn portion and said incoming fresh oil intimately contact each other for a relatively long period of time during descent through said treating zone and prior to intermixing with said fresh treating solution.

2. Apparatus for use in sweetening sour hydrocarbon oils with an aqueous copper treating solution which comprises a vertical treating conduit of relatively large cross-section, packing material substantially filling said conduit for enhancing contact and preventing separation, a first conduit for introducing fresh sour oil adjacent the top of said vertical treating conduit, a second conduit for introducing fresh copper treating solution adjacent the bottom of said vertical treating conduit, a centrifugal mixing pump connected with the bottom of said vertical treating conduit beyond the second conduit, a further vertical conduit of relatively small cross-section connecting said pump with a separating zone, and a by-pass conduit connected between said last-named vertical conduit and the first conduit whereby a portion of the contacted and agitated mixture of the treating solution and oil is mixed with incoming sour oil.

ELMER H. BENDER.
